(57) **CLAIM**

The ornamental design for a capsule for a tobacco suction tool, as shown and described.

DESCRIPTION

FIG. 1 is a perspective view of a capsule for a tobacco suction tool.

FIG. 2 is a front elevation view thereof. A rear elevation view is a mirror image of the front view. A top plan view and a bottom plan view are identical to the front view.

FIG. 3 is a left side elevation view thereof.

FIG. 4 is a right side elevation view thereof.

FIG. 5 is an enlarged cross-sectional view taken along the line 5-5 in FIG. 3 thereof.

FIG. 6 is an enlarged cross-sectional view taken along the line 6-6 in FIG. 3 thereof.

FIG. 7 is an enlarged cross-sectional view taken along the line 7-7 in FIG. 2 thereof.

FIG. 8 is an enlarged partial perspective view thereof; and, FIG. 9 is an enlarged left side elevation view thereof.

The broken lines shown in the drawings illustrate portions of the capsule for a tobacco suction tool that form no part of the claimed design.

The dot-dash lines show an unclaimed boundary which forms no part of the claimed design.
